1 Claim 10

ABSTRACT OF THE DISCLOSURE

The invention essentially comprises a wheeled chair or carriage comprising a framework including a footrest and seat between side supports, the said framework being maneuvered by hand operated driving wheels on each side and a castor wheel beneath or rearward of the seat of the chair or carriage.

In its preferred form the wheeled chair or carriage has a low center of gravity and is useful as a manoeuvrable children's toy.

The present invention relates to wheeled chairs, carriages or the like particularly adapted to safely seat children of tender years and be manually propelled by their users.

Many wheeled toys are known for example simulations of four-wheeled cars, crank driven trolleys, scooters, tricycles and bicycles.

These toys generally involve a degree of physical skill and coordination beyond that expected of children of tender years, say between 3 to 7 years old.

It is further to be noted that parents of young children, not infrequently purchase mobile toys of the kind indicated, which toys are inherently hazardous since they call for physical skills and judgement beyond the ordinary expectation for children of tender years.

The primary object of the present invention is to overcome the foregoing and other disadvantages of known mobile toys by providing such toys which are adapted to safe handling by children of tender years.

A further object of the invention is to provide such toys of relatively economical cost suited to the financial circumstances of parents of young children.

Another object is to provide mobile toys of the kind indicated having a low centre of gravity and consequent stability and suited for easy manoeuvrability within the confines of a home.

Other objects and advantages of the invention will be made apparent in the following description.

A wheeled children's toy having a low centre of gravity in accordance with the present invention comprises a framework including a seat and footrest between side supports, the said framework being supported by hand operable side wheels and a following castor wheel.

The invention is now more fully described with reference to one preferred embodiment illustrated in the accompanying drawings, in which:

FIGURE 1 is a perspective view of a wheeled chair or carriage; and

FIGURE 2 is a side elevated view of the chair or carriage illustrated in FIGURE 1.

In this embodiment, the frame 1 is formed of tubular steel having its opposite longitudinal sides bent upwardly to achieve attachment of the disc wheels 5 to their stub axles 6 which are anchored to the frame 1.

A tubular seat supporting member 2 longitudinally bisects the frame 1 and extends below the frame so as to accommodate a seat 3 between its seat supporting mem-

2

ber 2 and the under surface of the frame. Toward the end of the seat supporting member one or more footrests 4, 4' are located. The footrests are formed of tubular steel and welded to the seat supporting members and preferably are capped at their extremities to avoid injurious projections. The caps are advantageously formed of resilient natural or synthetic material moulded to fit the selected tubing size.

At its rearward end the seat supporting member 2, is flattened and upturned to provide a castor-wheel supporting bracket 9 which is apertured to admit and pivotably retain the upright stem of a castor wheel.

The side wheels 5 are provided with hand grips 7 retained on and turnable about their supporting shafts 8.

If desired the seat 3 may be provided with a back rest (not shown in the drawings).

A user of a wheeled toy in accordance with the invention sits on the seat 3 with feet on a footrest and manoeuvres the equipment by imparting a rotation to the side wheels. When both wheels are rotated in phase and in the same direction, the equipment moves either forward or backward. Wheels turned in opposite directions produce any desired change in direction of movement or the equipment can be caused to rotate in the one spot.

The relative height and size of the side wheels provide a safe support for a user of the applicant's equipment and the low center of gravity precludes any possibility of a user being able to overturn the equipment whatever manoeuvre is attempted.

In the preferred embodiment the tubular steel framework and footrest support are formed of non-corrodable steel alloys or chromium plated, permitting ready cleansing of the equipment. It will also be noted that the preferred construction is devoid of projections or corners against which a child may injuriously impinge or which would damage household furniture if the toy should be impelled against said furniture.

I claim:

1. A toy vehicle, comprising in combination a frame having substantially parallel side members which are upwardly bent, a pair of support wheels, means rotatably mounting said support wheels one to each of said side members and with their axes of rotation in alignment with each other, a castor wheel, means connecting said castor wheel to said frame rearwardly of said support wheels for pivotal movement about a vertical axis, a seat secured to the frame adjacent said castor wheel, a foot rest secured to said frame at a location forwardly of said seat, a stubshaft secured to each of said support wheels adjacent the outer periphery thereof and extending inwardly in the direction toward the other support wheel, and a hand grip member rotatably disposed on each of said stubshafts, so that an infant seated on said seat and having his feet supported on said footrest is able to propel and steer the vehicle by rotating the support wheels by means of said hand grips.
